(57) **CLAIM**

The ornamental design for an outdoor entertainment center, as shown and described.

DESCRIPTION

FIG. 1 is a perspective view of an outdoor entertainment center showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view thereof in a closed configuration;

FIG. 9 is a front elevation view thereof in the closed configuration;

FIG. 10 is a rear elevation view thereof in the closed configuration;

FIG. 11 is a left-side elevation view thereof in the closed configuration;

FIG. 12 is a right-side elevation view thereof in the closed configuration;

FIG. 13 is a top plan view thereof in the closed configuration; and,

FIG. 14 is a bottom plan view thereof in the closed configuration.

The broken lines depict portions of the outdoor entertainment center form no part of the claimed design.

1 Claim, 14 Drawing Sheets
